CARRIAGE-FEEDING DEVICE FOR
TYPEWRITERS

Hugo Schüler, Chemnitz, Germany, assignor to
Wanderer-Werke vorm. Winkelhofer & Jaenicke
Akt.-Ges., Schonau-Chemnitz, Germany

Application November 14, 1933, Serial No. 697,971
In Germany November 19, 1932

10 Claims. (Cl. 197—82)

The present invention relates to a carriage-feeding device for typewriters, preferably noiseless typewriters, in which the types are relieved of key action at the printing point and in which the letter-feed travel of the carriage is effected by the type carriers themselves or by their drive or link members through a universal bar.

The object of the invention is to provide a rapid and reliable carriage-feeding and particularly to prevent double and faulty letter-feed movements of the paper carriage, which frequently occur owing to rebound movements of the type carriers in previously known typewriters of this kind, on violent key operation.

The mechanism according to the invention overcomes difficulties which occur in typewriters of this kind due to the type carriers being confined in a very restricted space in front of the platen and all the drive members for the universal bar being concentrated in a small arc. The invention also aims at avoiding differences in the actuation of the universal bar by the middle and by the end type carriers respectively. The aforesaid advantages are achieved according to this invention which consists in that the operation of the members which effect the letter-feed movements of the carriage takes place during a path of the types which is shorter than half that path which they traverse between the point, where the influence of the keys ceases, and the point of printing.

The drawings illustrate one embodiment of the invention as applied by way of example to a noiseless typewriter and in which:

Figure 1 is a side view partly in section showing the complete drive mechanism of the type heads with the parts in normal position,

Fig. 2 is a similar view showing also a carriage escapement mechanism with the parts at the instant of beginning or finished operation of the carriage-feeding.

Fig. 3 is a side view of the escapement mechanism with fixed dog in engagement with the escapement wheel at the instant of impact of the type on the platen, and

Fig. 4 is a plan view of the universal bar.

In the typewriter illustrated, each type bar 1 which carries the type head 2a with the types is supported by two links 3 and 4. On depressing the key 5, the key lever 6 actuates, through an intermediate rod 7, a hook-shaped drive member 8 provided with a camming curve member. The camming curve member actuates a transmission lever 9 which through the agency of further transmission members 11, 12, and 13

operates the type bar 1 from the normal position shown in Fig. 1 toward the platen 14 until the key 5 and the key lever 6 reach the lowest position 5a and 6a indicated in Fig. 1 by dotted lines. During this movement the types 2 reach the position shown by the dotted line 15 in which the type bar 1 and the transmission members 9, 11, 12 and 13 are relieved of the action of the key 5, the outer end of the transmission lever 9 disengaging the camming curve member of the drive member 8, and continuing its further movement independently of the latter. The further movement of the actuated type 2 up to the printing point indicated by the dotted line 16, and that of the associated mechanism 9, 11, 12, 13, 1, 2, and 3 is effected exclusively under the action of momentum of the type bar 1 reinforced by the flyweight 10. The key 5, key lever 6, and drive member 8 do not participate in this further movement.

The operation of the members producing the letter-feed movement of the carriage is effected by means of lugs 18, one on each link 3, which move in dependence with the type bars 1 and which all operate on a universal bar 19. According to the present invention this actuation of the universal bar 19 and the other parts producing the carriage-feeding only begins when more than one-half of the path of the type 2 between the lines 15 and 16 has already been traversed, that is, when the corresponding type 2 has reached the position indicated in Fig. 2 by the dotted line 17. Experiment has shown that the distance of the type 2, corresponding to the beginning of letter-feed operation (line 35 17), from its printing point on the platen (line 16), should be so dimensioned that it amounts preferably to only one-fourth to one-fifth of the distance which exists at the instant of cessation of key movement and of the beginning 40 of momentum movement, between the type 2 (line 15) and the printing point (line 16).

Heretofore the actuation of the members producing the carriage-feeding in typewriters of this type began during the depression of the key 45 and the movement of the parts associated therewith, or it began in the instant in which the key movement ended and the action of momentum of the type bar began. The beginning of the letter-feed operation thus lay in front of or at the point of type movement designated in the present example by line 15. For this reason it frequently happened that the type 2 after complete printing had already returned to the position of line 15 before the return movement 55

of the key and of the key lever from the position designated by 5a and 6a into the position shown in full lines, so that the outer end of the transmission member 9 moving with the type 2 under 5 the influence of momentum would again strike against the camming curve member of the drive member 8 in its return movement. This produced a rebound and to and fro movement of the transmission members 9, 11, 12, 13, the 10 flyweight 10, and of the type bar 1, causing the type 2 to move beyond the position of line 15 and again toward the platen 14.

In the known mechanisms, moreover, as above described, even a small movement of the type 15 2 beyond the line 15 in the direction of the platen 14 initiates a new letter-feeding step of the carriage, so that on violent striking of the key 5 or on the latter sticking in the position 5a under a single manipulation, owing to the repeated rebound of the transmission members 20 9-13, two or more letter-feeding steps may take place. Contrary to this, when the carriage-feeding device according to the present invention is provided, no letter-feed movement of the 25 paper carriage is initiated when the type 2 after being freed of influence by the key, has moved beyond the line 15, so that the rebound movements when the transmission members strike against the drive members on the return of the 30 type 2 after impact against the platen 14 no longer produce double letter-feed movement of the paper carriage.

In the mechanism illustrated by way of example, the letter-feed actuating lugs 18 are integrally arranged on the front links 3 of the 35 type bars 1. In the position shown in Fig. 2 the actuating lug 18 bears against the universal bar 19. The universal bar 19 is attached by means of two angular projections 20 to a bridge 40 consisting of a web 21 and two similar laterally bent arms 22 and 22a. To these arms 22 and 22a there are jointedly connected at pivotal points 25 and 26 two pairs of links 23 and 23a, and 24 and 24a which are of equal length and 45 parallel to each other. The pair of links 23 and 23a is fixedly mounted on a shaft 27 which is journaled in a frame 29 fixed to the machine frame 28. Similarly the pair of links 24 and 24a is mounted on a shaft 30 which is also journaled 50 in the frame 29. The shaft 30 has a lever 31 fixedly connected thereto. On the link 24 there is provided a lug 32 in which is mounted an adjusting screw 33 which engages a stop 34 on the frame 29. By adjusting the screw 33 the 55 pair of links 24 and 24a jointedly connected to the other pair of links 23 and 23a by means of the arms 22 and 22a of the bridge 21, can be tilted whereby the position of the universal bar 19 relatively to the actuating lug 18 of the type 60 bar link 3 is varied. The link 24 and lever 31 are connected by a small bar 35 which is attached at one end to a tension spring 36 and at the other end to a pin 37 on the shaft 27, said spring serving to permanently urge the shaft 27 65 and the pair of links 23 and 23a to swing in a counter-clockwise direction. By this means the bridge 21, 22, 22a and the universal bar 19 at the end of a stroke are returned to the initial 70 position in which the adjusting screw 33 bears against the stop 34 of the frame 29.

While the type 2 traverses the path between the lines 17 and 16, the actuating lug 18 of the type bar link 3 moves the universal bar 19 downwards a small distance. This distance, owing 75 to the exact parallel guiding of the bridge

21, 22 and 22a, by means of the two pairs of links 23 and 23a, and 24 and 24a is equally large for all the actuating lugs 18 which are disposed around a very small arc.

The rotation of the shafts 27 and 30 is transmitted through a lever arm 31 on the shaft 30 to a rod 38 pivoted to said arm and the free end of the rod 38 carries an adjustable stop nut 39 which engages the known carriage dog rocker escapement 40. The dog rocker 40 is pivoted on 10 a fixed pin 41 and carries a fixed dog 42 and a loose dog 43.

During the letter-feed operation the fixed dog 42 is brought in known manner into engagement with the escapement wheel 44, the loose dog 43 15 moving out of engagement with this wheel and under the action of a weak spring snapping into the position corresponding to the next tooth of the escapement wheel 44. When printing is completed the fixed dog 42 releases the wheel 20 44 and the reengaged loose dog 43 permits the drive spring of the paper carriage to effect rotation of the escapement wheel 44 through one tooth and therefore a movement of the paper carriage by one letter space. 25

The cooperation between this known to and fro movement of the two dogs 42 and 43 and the very slight to and fro rotation of the shaft 30 produced by the universal bar 19 is made possible owing to the long lever 31 projecting from the 33 shaft 30 and also because the connecting rod 38 between this lever and the dog rocker 40 engages the latter at a certain distance from its pivot pin 41. This distance is smaller than the 38 distance of the two dogs 42 and 43 from the pivot pin 41 of the dog rocker 40 and smaller than the length of the lever 31.

The letter-feed operation initiated by the forward movement of the type toward the platen 14 in the position designated by the line 17, terminates during the return movement of the type 40 2 after printing on attaining the same position (line 17). Exceptionally rapid operation of the carriage letter-feeding is made possible by the very small movement of the universal bar 19 is transmitted with magnification by means of the lever 31 and the rod 38 to the escapement dogs 42 and 43.

In such noiseless typewriters, especially type- 50 writers with type bars, the type guide 45 is brought quite close to the platen 14 and the guide slot must be kept as short as possible because some of the type bars move at a very acute angle to the platen 14. Therefore the 55 type heads 2a must be very accurately and reliably guided at the instant of printing. In this connection the device according to the present invention is very advantageous because the operation of the letter-feed mechanism takes place 60 entirely in the interval in which the type head 2a carrying the types 2 is in the slot of the type guide 45. Thus while the universal bar 19 is moving and while the link 3 of the type bar 1 supplies the necessary energy for actuating the 65 letter-feed mechanism, the types 2 and their type heads 2a are guided on all sides so that departure from the printing direction is avoided. The letter-feed operation is reliably terminated 70 when a type head 2a leaves the slot guide, and a new carriage-feeding is initiated only when the next type head 2a has entered the guide 45. Thus very strong and rapid successive type 75 strokes against the platen may be effected with- 75

out disturbing the step by step feeding of the paper carriage.

I claim as my invention:—

1. In a typewriter, a paper carriage, means for the stepwise letter-feeding of the carriage, key levers, type heads, drive means connecting the key levers with the type heads during the initial portion only of the path of said heads and which type heads are disconnected from the drive means during the subsequent portion of their path to printing position, and means movable proportionally to the movement of the type heads and timed to impart actuating steps to the carriage letter-feed means only during the movement of the type heads on less than one-half of that portion of their path on which they are disconnected from said drive means.
2. In a typewriter, a paper carriage, means for the stepwise letter-feeding of the carriage, key levers, type heads, a type guide arranged quite close to the platen, drive means connecting the key levers with the type heads during the initial portion only of the path of said heads and which type heads are disconnected from the drive means during the subsequent portion of their path to printing position, and means movable proportionally to the movement of the type heads and timed to impart actuating steps to the carriage letter-feed means only during the movement of the type heads on less than one-half of that portion of their path on which they are disconnected from said drive means during which movement the type heads are guided in the said type guide.
3. A carriage-feeding device for typewriters, especially noiseless typewriters, in which the type bars are relieved of key action on a portion of their path adjacent the printing point, comprising an escapement mechanism for carriage letter-feeding, and means for actuating the escapement mechanism by the movement of the type bars carrying the types, said means being arranged to actuate the escapement mechanism only during the movement of the types adjacent the printing point on a path which is smaller than half the length of the portion of the path on which the types are relieved of key action.
4. A carriage-feeding device according to claim 3, in which the escapement mechanism is actuated by means of a universal bar supported by two parallel pairs of links so that the bar is moved an equal amount by all of the type bars during their actuating movement, and in which an adjustable stop is provided on one of the links to adjust the initial position of the universal bar.
5. In a typewriter, a paper carriage, means for the stepwise traverse of the carriage, key levers, type heads, driving connections between the key levers and type heads and adapted to disconnect said heads from said levers at an intermediate point of the travel of the heads towards the printing point, and means connected with said type heads and so located as to engage operatively the carriage traverse means only in that part of the travel of the disconnected type heads

lying immediately in front of the printing point and less than half the distance between the printing point and said intermediate point.

6. In a typewriter, a frame; a paper carriage; an escapement mechanism for carriage letter-feeding; key levers; type heads; driving connections between the key levers and the type heads and adapted to disconnect said heads from the levers at an intermediate point of the travel of the heads towards the printing point and a pair of links jointed to each head and pivoted in the frame; means for actuating the escapement mechanism, said means comprising a universal bar and intermediate members between the universal bar and the escapement mechanism; and projections on one of the links of each pair, all of said projections being so located as to engage operatively said universal bar, and said universal bar and said intermediate members being so arranged that the escapement mechanism is actuated only in that part of the travel of the disconnected type heads lying immediately in front of the printing point and less than half the distance between the printing point and said intermediate point.

7. In a typewriter, a frame; a paper carriage; an escapement mechanism for carriage letter-feeding; key levers; type heads; driving connections between the key levers and the type heads and adapted to disconnect said heads from the levers at an intermediate point of the travel of the heads towards the printing point and a pair of links pivoted in the frame and jointed to each head, one of said links being nearer the paper carriage than the other link; means for actuating the escapement mechanism, said means comprising a universal bar and intermediate members between the universal bar and the escapement mechanism; and projections on the links nearer the paper carriage, all of said projections being so located as to engage operatively said universal bar, and said universal bar and said intermediate members being so arranged that the escapement mechanism is actuated only in that part of the travel of the disconnected type heads lying immediately in front of the printing point and less than half the distance between the printing point and said intermediate point.

8. A typewriter according to claim 6, in which the projections are located close to the pivots of the links with the frame.

9. A typewriter according to claim 6, in which the operative movement of the universal bar from its normal position is guided by links, and means operative between one of said links and the frame are provided to vary said normal position relatively to that of the projections.

10. A typewriter according to claim 6, in which the projections are located close to the pivots of the links with the frame, and the operative movement of the universal bar from its normal position is guided by links while means operative between one of said links and the frame are provided to vary said normal position relatively to that of the projections.

HUGO SCHÜLER.
